UNITED STATES PATENT OFFICE.

JOHN WOLFE, OF CLEVELAND, OHIO, ASSIGNOR, BY DIRECT AND MESNE ASSIGNMENTS, TO THE AURORA SPECIALTY CO., OF CLEVELAND, OHIO, A CORPORATION OF OHIO.

UMBRELLA STRUCTURE.

No. 874,648.

Specification of Letters Patent.

Patented Dec. 24, 1907.

Application filed February 9, 1907. Serial No. 356,506.

To all whom it may concern:

Be it known that I, JOHN WOLFE, a citizen of the United States, resident of Cleveland, county of Cuyahoga and State of Ohio, have invented a new and useful Improvement in Umbrella Structures, of which the following is a specification, the principle of the invention being herein explained and the best mode in which I have contemplated applying that principle, so as to distinguish it from other inventions.

This invention relates to umbrella structures.

The object of this invention is to provide an umbrella which may be turned inside out or reversed, under extraordinary wind pressure, without injury to the frame or cover thereof.

My invention, therefore, consists in providing an umbrella in which the members composing the frame have a fixed normal length when the umbrella is open or shut but which are capable of a relative contraction and elongation so as to permit the frame to yield and assume a position of least resistance under abnormal wind pressure.

My invention further consists in the features of construction and combination of parts as described in the specification, pointed out in the claims and illustrated in the accompanying drawings.

In the accompanying drawings Figure 1 is a central section showing in full lines the position of the members when the umbrella is in its normal open position and in dotted lines the position of the members when the umbrella is reversed. Fig. 2 is an enlarged detail view, mostly in section, of a portion of the frame of the umbrella. Fig. 3 is an enlarged detail view showing a modified construction of the ribs and stretcher rods. Fig. 4 is a section on line 4—4, Fig. 3.

Again referring to the drawings 1 represents the umbrella rod which is preferably made of hollow steel tubing and at the upper end thereof is rigidly secured a notch 2 to which the ribs are pivotally secured in such a manner that they are free to swing through an arc greater than ninety degrees. Each rib consists of two sections 3 and 4 which are arranged to telescope with each other. The rib section 3 is pivotally secured to the notch and the rib section 4 is provided with a bore 5 arranged to receive

the free end of the section 3. In the wall of the bore 5 is formed a slot 6 and a pin 7 is secured in the rib section 3 and is arranged to extend into the said slot 6 and the arrangement is such that when the rib is extended its normal length the pin is at the end of the slot 6 nearest to the umbrella rod so that the rib can never be increased or lengthened beyond its normal length and therefore the rib has a fixed length when the frame is opened or closed, but can be contracted or shortened. On the outer end of the rib section 4 is arranged a sleeve 10 which is free to slide thereon. The movement of the sleeve 10 on the rib section 4 is limited by two projections or lugs 13 and 14 and the arrangement is such that when the umbrella frame is in its normal open or closed position the sleeve will abut against the lug 13 which is nearest the free end of the rib section. On the umbrella rod is slidably arranged a runner 15 of the usual construction and on the rod is arranged the usual spring dog 16 which holds the runner in its normal position when the umbrella is open but does not prevent the runner from moving up further on the rod under abnormal conditions.

The stretcher rods are formed in two sections 17 and 18. The section 17 is pivotally secured at one end to the runner and in the free end is formed a bore 19 arranged to receive the end of the section 18 and the other end of said section 18 is pivotally secured to the sleeve 10 on the rib to which the stretcher rod is to be attached. In the wall of the bore 19 is formed a slot 20 and a projection 21 is arranged on the section 18 and extends into the said slot 20 and the arrangement is such that when the umbrella frame is in its normal open or closed position the projection 21 on the stretcher rod section 18 will be at the end of the slot 20, in the stretcher rod section 17, nearest to the umbrella rod so that the stretcher rod is free to elongate beyond its normal length but cannot contract. Within the upper end of the umbrella rod is arranged a coil spring 25 which is secured at its upper end to a stationary pin 26 and at its lower end abuts against a pin 27 which extends through a longitudinal slot formed in the umbrella rod and when the frame of the umbrella is in its normal open position the runner will come in contact with said pin and the pressure of the spring will tend to hold the runner against

upward movement. The frame is provided with a suitable cover 30.

In Figs. 3 and 4 are shown modified construction of a rib and stretcher rod. In this 5 construction the stretcher rod is formed of two telescoping members or sections 32 and 33 and each section is formed of a piece of angle iron, one of which is arranged to slide within the other. The outer section is provided with straps 35 which are arranged to hold 10 it in position. A lug 38 is formed on the section 33 which prevents the stretcher rod from contracting while leaving it free to 15 lengthen. In this construction the rib 36 is formed in one piece and the stretcher rod is pivotally secured to a lug 37 formed integral with the rib.

It will be understood from the foregoing 20 description that when the umbrella is opened or closed in the normal way there is no movement of the sections of the ribs or of the sections of the stretcher rods on each other, but if, when the umbrella is open, sufficient 25 wind pressure is brought to bear upon the umbrella, then the rib sections will slide in upon each other shortening the rib, and the stretcher rod sections will slide out upon 30 each other lengthening the stretcher rod and therefore the whole frame of the umbrella will yield to the wind pressure and be reversed, and there will be little liability of it being broken or strained.

I therefore particularly point out and distinctly claim as my invention:

1. In a reversible umbrella, the combination of a rod and a cover supporting frame arranged on said rod, said frame comprising a plurality of members arranged to form 40 ribs and stretcher rods, said members having a fixed length when the umbrella is open or closed, and means for permitting a relative elongation and contraction of said members when a pressure is exerted on the inside of 45 said frame tending to reverse said frame.

2. In a reversible umbrella the combination of a rod and a cover supporting frame comprising a notch rigidly mounted at the upper end of said rod, a series of ribs pivotally secured to said notch and free to swing through an arc greater than ninety degrees, a runner arranged on said rod, stretcher rods pivotally secured to said runner and an operative connection arranged between each 50 stretcher rod and the rib to be extended thereby, said connection having the same fixed position on the rib when the umbrella is in its normal open or closed position and capable of moving on said rib when a pressure is exerted on the inside of said frame tending to reverse said frame.

3. In a reversible umbrella, the combination of a rod and a cover supporting frame arranged thereon, said frame comprising a 60 notch secured at the upper end of said rod,

a series of ribs pivotally secured to said notch, each rib comprising two telescoping sections arranged so that the rib has a fixed length when the frame is in its normal open position or its closed position and capable of contraction when the frame is opened beyond its normal position, a runner arranged on said rod and a series of stretcher rods, each stretcher rod being secured at one end to said runner, and at its opposite end 70 to a rib.

4. In a reversible umbrella, the combination of a rod, and a cover supporting frame comprising a notch mounted at the upper end of said rod, a series of ribs pivotally secured 80 to said notch, a runner arranged on said rod and a series of stretcher rods, each stretcher rod being secured at one end to said runner, and at its opposite end to a rib and comprising two telescoping sections capable only of 85 elongation beyond their normal length.

5. In a reversible umbrella, the combination of a rod and a cover supporting frame comprising a notch mounted at the upper end of said rod, a series of ribs pivotally secured 90 to said notch, a sliding member arranged on each rib, means for limiting the movement of said sliding members on said ribs, a runner arranged on said rod, and a series of stretcher rods, each stretcher rod being secured at one end to said runner, and at its opposite end to a rib and comprising two telescoping sections capable only of elongation 95 beyond their normal length.

6. In a reversible umbrella, the combination of a rod and a cover supporting frame arranged thereon, said frame comprising a notch secured at the upper end of said rod, a series of ribs pivotally secured to said notch, each rib comprising two telescoping 100 sections arranged so that the rib has a fixed length when the frame is in its normal open position or its closed position and capable of contraction when the frame is opened beyond its normal position, a sliding member arranged on each rib, means for limiting the movement of said sliding members on said ribs, a runner arranged on said rod, and a series of stretcher rods, each stretcher rod being secured at one end to a sliding 105 member on a rib, and at its other end to said runner.

7. In a reversible umbrella, the combination of a rod and a cover supporting frame arranged thereon, said frame comprising a notch secured at the upper end of said rod, a series of ribs pivotally secured to said notch, each rib comprising two telescoping sections arranged so that the rib has a fixed length when the frame is in its normal open position 120 or its closed position and capable of contraction when the frame is opened beyond its normal position, a sliding member arranged on each rib, means for limiting the movement of said sliding members on said ribs, a 125

runner arranged on said rod, and a series of stretcher rods, each stretcher rod being secured at one end to said runner, and at its opposite end to a rib and comprising two telescoping sections capable only of elongation beyond their normal length.

8. In a reversible umbrella, the combination of a rod and a cover supporting frame arranged thereon, said frame comprising a notch secured at the upper end of said rod, a series of ribs pivotally secured to said notch, each rib comprising two telescoping sections, one of said sections being provided with a slot and the other section being provided 15 with a projection arranged to extend into said slot and the arrangement is such that when the frame is in its normal open or closed position the projection on one section of a rib will be at one end of the slot on the other 20 section of the rib preventing the elongation of said rib while permitting the contraction thereof, a runner arranged on said rod and a series of stretcher rods operatively connecting said ribs and said runner.

25 9. In a reversible umbrella, the combination of a rod and a cover supporting frame comprising a notch mounted at the upper end of said rod, a series of ribs pivotally secured to said notch, a runner arranged on 30 said rod and a series of stretcher rods, each stretcher rod being secured at one end to said runner, and at its opposite end to a rib and comprising two telescoping sections, one of said sections being provided with a slot and 35 the other section being provided with a projection arranged to extend into said slot and

the arrangement is such that when the frame is in its normal open or closed position the projection on one section of a rod will be in one of the slots on the other section of the rod preventing the contraction of said rod while 40 permitting the elongation thereof.

10. In a reversible umbrella, the combination of a rod and a cover supporting frame comprising a notch mounted at the upper 45 end of said rod, a series of ribs pivotally secured to said notch, a runner arranged on said rod, a series of stretcher rods forming operative connection between said runner and said ribs and means for yieldingly holding 50 said runner a predetermined distance from said ring.

11. In a reversible umbrella, the combination of a rod and a cover supporting frame comprising a notch mounted at the upper 55 end of said rod, a runner arranged on said rod, a plurality of members arranged to form ribs and stretcher rods, said members having a fixed length when the umbrella is opened, or closed and means for permitting a relative 60 elongation and contraction of said members when pressure is exerted on the inside of said frame and means for yieldingly holding said runner a predetermined distance from said notch.

Signed by me, this 19th day of January, 1907.

JOHN WOLFE.
